UNITED STATES PATENT OFFICE.

MARY JANE HENNESSY, OF NEW KENSINGTON, PENNSYLVANIA.

WAIST-SHAPING MEANS.

SPECIFICATION forming part of Letters Patent No. 694,641, dated March 4, 1902.

Application filed June 24, 1901. Serial No. 65,767. (No model.)

To all whom it may concern:

Be it known that I, MARY JANE HENNESSY, a citizen of the United States, and a resident of New Kensington, county of Westmoreland, 5 and State of Pennsylvania, have invented certain new and useful Improvements in Waist-Shaping Means, of which the following is a specification, reference being had to the accompanying drawings, forming a part thereof, in which similar characters of reference indicate corresponding parts.

This invention relates to waist-shaping means, and especially to a belt-buckle for use in connection with a corset or a steel attached to such corset for producing the well-known long-waist effect, the main object of the invention being to provide means for securing a leather, canvas, or other buckle-belt to the corset or to a separate steel or other 20 member adapted to form the long waist.

The long-waist effect has been produced heretofore by means of a long-waisted corset and also by means of a separate long-waist-forming steel attachable to the corset and 25 having a tape adapted to be wrapped around the body of the wearer and then have the waist of the dress tucked under such tape; but with these long-waist-forming devices it has been necessary to wear a soft-ribbon belt 30 which can be tucked under the tape, and it has not been possible to wear with such waist-shaping means a stiff belt having a buckle, and it is my object to provide for the wearing of such a belt.

35 In the drawings, Figure 1 is an illustrative view showing one mode of producing a long-waist effect. Fig. 2 is a similar view showing a stiff belt having a buckle and secured to a waist-shaping device. Fig. 3 is an enlarged 40 view illustrating in detail a stiff belt having a buckle provided with means for attachment to a long-waist-forming device. Fig. 4 is a transverse section of a belt-buckle having a socket with a waist-shaping steel therein.

45 In producing the long-waist effect with waist-shaping means separate from the corset it has been customary to make use of a somewhat short steel, such as 2, having one or more eyelet-holes 3, adapted to be hooked over a corresponding clasp or clasps of a corset 50 4. At the lower end thereof this steel 2 usually has secured thereto a long tape or string

5, adapted to be passed two or more times around the body of the wearer and preferably tied in front to assist in holding the steel 55 in proper position, the tape being usually inserted through slots 6 6 at the lower end of the steel. With this steel the edges 7 of the wearer's dress-waist are tucked under the oblique portions 5' of the tape to produce the 60 long-waist effect and a ribbon belt tucked in place in substantially the same manner.

My present improvements are designed to permit the use of a stiff belt having a buckle when it is desired to wear such a belt with a 65 long-waist-shaping device, and I accomplish this result by providing means for attaching the belt-buckle directly to the lower end or point of the long-waist-forming means whether the latter be a corset or a separate 70 long-waist-forming steel, such as that shown at 2.

B designates a belt, and b a belt-buckle, of any suitable construction, except that the latter has connecting means for attachment to 75 the steel 2, said buckle having in this case a recess or socket at the rear side thereof and near the lower edge of the buckle, said recess being of such size and shape and being so located as to receive the lower end or point 2' 80 of the steel 2 and hold the same firmly, the belt, and hence the belt-buckle, having a constant tendency to work up at the front of the waist and the steel a corresponding tendency to press the belt and the buckle down. The 85 recess or socket 8 may be formed advantageously by brazing or soldering a substantially trough-shaped or U-shaped piece of sheet metal 9 to the back of the buckle, the inner rear wall 10 being preferably inclined upwardly and to the rear to accommodate itself more readily to the positions and movements of the steel 2, wedged in place between it and the rear wall of the buckle.

It will be evident that the devices herein 95 described constitute a very simple and effective means for producing the long-waist effect and holding the lower edge of the dress-waist in position and at the same time permitting a stiff belt to be worn therewith.

Having thus described my invention, what I claim as new, and desire to secure by Letters Patent, is—

1. A belt-buckle having at the rear side

- thereof a recess open at its upper side and adapted to receive the end of a waist-shaping device, the inner rear wall of said recess being inclined to the rear.
5. A belt-buckle having at the lower edge of its rear side a recess open at its upper side and adapted to receive the end of a waist-shaping device.
3. A belt-buckle having at the rear side thereof a rearwardly-projecting member forming between it and the buckle a socket adapted to receive the end of a waist-shaping device.
4. A belt having a buckle provided with a socket adapted to receive the end of a waist-shaping device.
15. The combination with a waist-shaping
- steel constructed for attachment to a corset, of a belt having a buckle provided at its rear side with a steel-receiving socket. 20
6. The combination with a waist-shaping steel constructed for attachment to a corset, of a tape adapted to be secured to said steel and passed around the body of the wearer, and a belt having a buckle provided at its 25 rear side with a steel-receiving socket.
- In testimony that I claim the foregoing as my invention I have signed my name, in presence of two witnesses, this 18th day of June, 1901.

MARY JANE HENNESSY.
